PINKING ATTACHMENT OR MACHINE

Benjamin H. Livinson, New York, N. Y., and
Henry F. Webster, St. Louis, Mo.

Application May 31, 1933, Serial No. 673,619

6 Claims. (Cl. 112—128)

The invention is a device for pinking or cutting notches or openings in material which may be used as an independent unit or attached to a sewing machine and operated by the needle bar thereof in such a manner that it will pink material as it is drawn thru the sewing machine by the presser foot thereof.

All materials have a tendency to fray at the raw or cut edges and it has been found that cutting the edge in a zig-zag line checks or prevents fraying or raveling thereof.

It is, therefore, the purpose of this invention to provide a pinking device that may readily be used independently, or adapted to any sewing machine, which will trim the edges of material passed therethru, in a zig-zag line, which is commonly known as "pinking".

This invention therefore relates to a device having a cutter which may be adjusted to make cuts of different sizes and which is adapted to cut or pink all kinds of material for garments or any other purpose. Pinking is generally used to prevent fraying of the edges of the material beyond the seams of different types of garments such as dresses, under garments, suits, coats, or any type of garment, and may also be used on material as a finish for the edges, and for any other purpose. Pinking is also used for the edges of oilcloth as used for table or shelf covers or for any other purpose, or wherever selvage edges may be desired.

The object of the invention is, therefore, to provide a device that may readily be adapted to a sewing machine for pinking edges of material as it is passed thru the machine.

Another object is to provide a pinking attachment for sewing machines which may readily be operated by the needle bar of the machine.

Another object is to provide a pinking attachment for sewing machines which may be positioned upon the machine in such a manner that material will be drawn thru the attachment and cut with each movement thereof.

A further object is to provide a pinking attachment for sewing machines for cutting the edges of materials passing therethru to check or prevent fraying of the edges.

A still further object is to provide a pinking attachment which may readily be used to cut all kinds of materials.

And a still further object is to provide a pinking attachment for sewing machines which is of a simple and economical construction.

With these ends in view the invention embodies

stand, a die on the base of said stand, a lever adapted to operate said cutter, the end of which may be placed over the thumb screw of the needle bar of a sewing machine, and means adjusting the stroke of said lever and cutter.

Other features and advantages of the invention will appear from the following description taken in connection with the drawing, wherein:

Figure 1 is a view showing the attachment as it may be used on a sewing machine.

Figure 2 is a side elevation of the attachment.

Figure 3 is a front elevation of the attachment.

Figure 4 is a sectional plan view showing the base.

Figure 5 is a view showing a piece of material, 15 with a pinked edge.

Figure 6 is a view showing an alternate design in which the upper part of the cutter is slidably held in a dovetailed slot in the head of the machine.

Figure 7 is a side elevation of the cutter shown in Figure 6.

Figure 8 is a plan view of the cutter shown in Figure 6 with the connection at the upper end of the cutter omitted.

Figure 9 is a detail showing an alternate means for connecting the cutter to the operating lever.

Figure 10 is a detail showing another alternate design in which the cutter and slot in which it is slidably held are round.

Figure 11 is a view showing a piece of material having diamond shaped openings cut therein by the device.

Figure 12 is a similar view showing semi-circular openings.

In the drawing the attachment is shown as it would be made wherein numeral 1 indicates the stand, numeral 2 the presser foot of a sewing machine, and numeral 3 a piece of material.

The stand 1 is made with a base 4 having a slot 5 in a projection at one side thereof thru which it may be held by a screw or screws to the plate of a sewing machine as shown in Figure 1, and in another projection 6 at the front of the base is an opening 7 over which a die 8 may be placed and held by screws 9, as shown. The holes in the die 8, thru which the screws 9 pass are slotted or elongated, as shown in Figure 8, so that the die may be adjusted in relation to the cutter.

The die is provided with a triangular shaped opening 10, in the design shown, however it will be understood that this opening may be of any other shape or design to form pinking of any shape or type. A cutter 11 is slidably held in a slot 12 in the head 13 of the stand, and in the

design shown in Figures 1, 2, and 3, plates 14 and 15 are provided at the upper and lower ends of the slot to hold the cutter therein, however, it may be held by any other means or the sides of the upper part may be inclined or dovetailed, round, triangular, or of any shape so that the cutter may be held in the groove without the plates 14 and 15. At one side of the lower part of the head 13 is an extension 16 to which a lever 17 is pivotally attached by a pin 18, and in the design shown in Figures 1, 2, and 3 this lever is attached to the cutter 11 by a link 19 thru screws 20 and 21. This lever may also be directly attached to the cutter, or attached to the upper end thereof, as shown in Figures 6 and 7, or connected thereto in any manner or by any means. At the outer end 22 of the lever is a plate 23 having a slot 24 therein which may be placed over a screw 25 on the needle bar of a sewing machine, as shown in Figure 1, so that as the needle bar travels upward and downward it will move the lever 17 upward and downward and thereby operate the cutter 11 with a reciprocating movement. The plate 23 is adjustably held to the end of the lever 17 so that it may be moved upward or downward to adjust the travel of the lever in relation to the movement of the needle bar, and it will be noted that it is pivotally attached by a screw 26 and provided with a slot 27 thru which another screw 28 may extend, and the screws may be tightened to hold the plate in any position. The lower end of the cutter 11 is provided with a triangular shaped point 29 to correspond with the opening 10 in the die 8, and it will be understood that the point of the cutter may also be of any other shape to correspond with dies of different shapes to cut pinking of any shape or design.

In the design shown in Figures 6, 7, and 8 the plates 14 and 15 are omitted and the slot 12 formed with inclined edges to correspond with similar edges of the cutter so that the cutter may be held therein without the use of the plates. It will also be understood that the cutter and slot may be made round, as shown in Figure 10, in which the cutter is indicated by the numeral 30, and the slot by the numeral 31, or of any other shape or design. In the design shown in Figure 10 one side of the cutter is provided with a slot 32 in which a point 33 of a set screw 34 may extend as shown. It will be understood, however, that any other means may be used for holding the cutter in position, and it will also be understood that the lower or cutting end of the cutter 30 may be pointed or of any shape. In the design shown in Figures 6 and 7 a clip 35 is attached to the upper end of the cutter by a screw 36 and this is pivotally attached to a link 37, thru a pin 38 and the lower end of the link 60 is pivotally attached to the lever 17 thru a pin 39. The device may otherwise be constructed as shown in Figures 1, 2, and 3, and it will also be understood that the connection between the lever and cutter shown in Figures 1, 2, and 3 may be used with the device shown in Figure 6, or the connection shown in Figure 6 may be used with the device shown in Figure 1.

The device may also be used for cutting material for hemstitching so that a diamond shaped cutter may be provided to cut openings 40 in a piece of material 41, as shown in Figure 11, and it will also be understood that semi-circular notches 42 may be cut in the edge of the material instead of the V shaped notches as shown in Figure 75. It will also be understood that these notches

may be of any type or design and may be made in the edge or edges or in any part of the material.

It will be understood that changes may be made in the construction without departing from the spirit of the invention. One of which changes 5 may be in the use of a stand of any other type or description, another may be in the use of other means for holding the stand to the sewing machine, another may be in the use of a cutter bar of any other type, and still another may be in the use 10 of other means for connecting the cutter to the needle bar to provide reciprocating motion therefor.

The construction will be readily understood from the foregoing description. In use the device 15 may be attached to the machine and material to be pinked may be placed over the base and fed under the presser foot, and as the machine operates the feeding mechanism of the sewing machine will draw the material across the die and 20 the needle bar will move the cutter upward and downward to cut the edges of the material as shown in Figures 4 and 5. It will be understood that any other means may be used for feeding the material thru the device which may be independent of, or in combination with the presser foot of the sewing machine. It will also be understood that the lever 17 may be omitted and the cutter 25 operated by any other means so that it may be provided as an independent unit and operated by 30 any means. Any other type of feeding mechanism, similar to the presser foot of a sewing machine, or of any description may be incorporated in the foot or base of the device and this may be used independent of the sewing machine or in 35 combination with a sewing machine, as may be desired.

The die is so positioned that it will engage the surface of the cutter with slight friction and the continual moving up and down will sharpen the 40 edge of the cutter. Adjusting the travel of the cutter makes it possible to cut only with the point thereof, or with more of the cutting surface so that it is possible to cut shallow or deep pinking. It 45 has been found that cutting material in this manner provides a selvage edge which prevents fraying or raveling and at the same time provides a unique finish.

Having thus fully described the invention what 50 we claim as new and desire to obtain by Letters Patent, is:

1. In a pinking attachment adapted to be used on sewing machines, a triangular shaped cutter, means slidably and vertically mounting said cutter on the sewing machine, said mounting means having a groove corresponding with the shape of the cutter adapted to hold the cutter in perfect alignment, means operating said cutter from the needle bar of the machine, a stationary die adapted to receive said cutter, and means adjusting the position of said die to engage the cutter to sharpen the cutting edges thereof as the cutter operates.

2. An attachment for sewing machines, or the like, comprising a stand adapted to be attached to the bed plate of a sewing machine having a vertically positioned head with a groove therein, a cutter slidable in said groove, a lever pivotally mounted at one side of said head extending across the face of said groove and with the free end 65 adapted to engage a thumb screw on the needle bar of the sewing machine, and means pivotally attaching said lever to the cutter to move the cutter upward and downward with the needle bar.

3. An attachment as described in claim 2 in 75

which the attaching means of the lever to the cutter comprises a link pivotally attached to the lever and cutter.

4. An attachment as described in claim 2 in which the means by which the outer end of the lever is attached to the needle bar is adjustable to regulate the travel of the cutter.

5. The combination with a stand having a vertically positioned head with a vertical groove therein and a base from which the head is supported by a goose-neck arm providing clearance under the head; of a cutter slideable in said groove and a lever pivotally mounted on one side of said head extending across said cutter, pivotally at-

tached to the cutter, and having means at the opposite or free end for engaging the needle bar of a sewing machine with the base of said stand attached to the bed plate of the sewing machine and in which the needle bar moves the cutter upward and downward thru said lever. 5

6. A combination as described in claim 5 in which a plate having an opening therein corresponding with the shape of the cutter is adjustably mounted on the bed plate with the opening 10 positioned to correspond with the cutter.
